UNITED STATES PATENT OFFICE.

ADOLF MIERSEE, OF COLOGNE, GERMANY.

STEAM-JET APPARATUS.

1,095,910.

Specification of Letters Patent. Patented May 5, 1914.

Application filed August 28, 1913. Serial No. 787,116.

To all whom it may concern:

Be it known that I, ADOLF MIERSEE, a subject of the King of Prussia, German Emperor, residing at Cologne, in the Kingdom 5 of Prussia, German Empire, have invented certain new and useful Improvements in Steam-Jet Apparatus, of which the following is a specification.

This invention relates to a steam jet apparatus the nozzle of which is constructed in such a manner that it can be removed or adjusted during the working of the apparatus. The apparatus has further a central admission of air and it can be mounted 10 in steam heating plants so that the steam which circulates in the plant returns to the apparatus, the efficiency of the heating plant being thus considerably increased.

The characteristic feature of the invention 20 consists in the adjustability and interchangeability of the nozzle core during the working. A nozzle with invariable cross section will naturally fail when the admission of fresh steam varies, as is for example 25 the case with sudden differences of temperature, each nozzle section requiring a determined quantity of steam for its proper working. For this reason it is very important that the cross section of the nozzle 30 can be regulated in order to insure a proper and continuous working of the steam jet apparatus. If the quantities of fresh steam admitted vary considerably it is not sufficient 35 that the cross section of the nozzle can be regulated but the nozzle must be removable or interchangeable.

As steam jet apparatuses are used only 40 for large heating plants the stopping of the plant requires much time and causes a certain loss of power which is avoided by the improved nozzle. The invention is particularly useful where heating plants are used 45 for mechanically drying materials as in such cases the shutting off of the steam would be particularly onerous.

When heating plants with steam jet apparatus are being started air is generally admixed with the fresh steam for reducing the tension of the steam and consequently increasing the volume of the same. With the apparatuses of known construction the air inlets are arranged in such a manner that the steam jet apparatus draws in the air only if the cross sections of the air inlets are 55 of determined proportion with regards to the cross sections of the ports for the steam

which is drawn in and with the quantity of the active fresh steam. This arrangement is not practicable with heating plants so that the admission of air is generally not properly effected. According to the invention, the air inlet is arranged in the core of the nozzle and consequently surrounded by fresh steam so that the sucking in of the air is insured.

In the accompanying drawings the invention is shown by way of example.

Figure 1 shows the nozzle core in working position the register being lifted. Fig. 2 shows the nozzle core withdrawn into the fore-chamber which is shut off from the nozzle chamber proper by the register.

The fresh steam flows in the direction of the arrows from the inlet 1 through the nozzle to the outlet 2; the return steam 75 flows in at 3 and flows out through the outlet 2. The nozzle core 4 is screwed upon a hollow spindle 10 the rear end of which is screwed into the casing and adapted to be screwed in or out by means of a hand wheel 5. If the regulation of the nozzle by means of the hand wheel 5 is not sufficient the nozzle core 4 must be removed and a nozzle core of a different shape inserted which of course is possible only if the nozzle core has 80 been removed from the apparatus. With this object in view the register 7 is arranged in such a manner that it drops automatically as soon as the nozzle core 4 has been sufficiently moved back, whereby the steam 85 apparatus is shut off. The fore-chamber 8 is packed by means of a stuffing box 9. Only after the register 7 has dropped air can get 90 into the fore-chamber 8 owing to the special shape of the nozzle core 4 so that, if the 95 nozzle core has been sufficiently withdrawn the steam in the fore-chamber expands and the nozzle can be removed. The fresh steam flowing in through the inlet 1 surrounds the nozzle 4 whereby a partial 100 vacuum is produced at the front end of the central channel of the nozzle core and air is drawn in through the spring influenced air valve 11 arranged at the end of the central bore of the spindle 10. The inflow of the 105 air is stopped if the pressure in the heating plant has increased so that the valve 11 is automatically closed.

I claim:—

Steam jet apparatus comprising in combination with the casing having inlets for the fresh steam and for the return steam and an

outlet for the heating steam, a fore-chamber at the rear end of the casing, a register adapted to shut off said fore-chamber from said casing a nozzle in said casing, a movable nozzle core in said nozzle, a hollow screw spindle into the front end of which said removable nozzle core is screwed, an outwardly threaded rear part of said spindle guided in a correspondingly threaded part 10 of the casing, a hand wheel upon the rear

end of said spindle, and a spring influenced valve closing the rear end of the bore of the spindle, substantially as described and shown and for the purpose set forth.

In witness whereof I have hereunto set my hand in the presence of two witnesses,

ADOLF MIERSBÉ.
